US00D695693S

(12) **United States Design Patent**
Lee et al.

(10) **Patent No.:** US D695,693 S
(45) **Date of Patent:** ** Dec. 17, 2013

(54) **OUTLET**

(71) Applicant: **Powertech Industrial Co., Ltd.**, New Taipei (TW)

(72) Inventors: **Yu-Lung Lee**, New Taipei (TW); **Yu-Hsuan Chen**, New Taipei (TW)

(73) Assignee: **Powertech Industrial Co., Ltd.**, New Taipei (TW)

(**) Term: **14 Years**

(21) Appl. No.: **29/450,400**

(22) Filed: **Mar. 18, 2013**

(30) **Foreign Application Priority Data**

Jan. 9, 2013 (TW) 102300217

(51) **LOC (9) Cl.** 13-03

(52) **U.S. Cl.**

USPC **D13/152**

(58) **Field of Classification Search**

USPC D13/139.5, 161, 137.2, 137.1, 133, 127,

D13/124, 139.8, 139.1, 154, 156, 184, 199,

D13/153, 155, 152, 177, 138.1; D11/90;

D14/205, 228; D7/300.2

See application file for complete search history.

(57) **CLAIM**

The ornamental design for an “outlet,” as shown and described.

DESCRIPTION

FIG. 1 is a perspective view of an outlet showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view showing the practical usage thereof.

The broken lines depict portions of the outlet which form no part of the claimed design.
